UNITED STATES PATENT OFFICE

168,502

BISCUIT BOX

Armand M. Guior, Brooklyn, N. Y.

Application August 6, 1952, Serial No. 20,924

Term of patent 14 years

(Cl. D44—1)

To all whom it may concern:

Be it known that I, Armand M. Guior, a citizen of the United States, residing at Brooklyn, in the county of Kings and State of New York, have invented a new, original, and ornamental Design for a Biscuit Box, of which the following is a specification, reference being had to the accompanying drawing, forming part thereof.

In the drawing:

Fig. 1 is a side elevational view of a biscuit box, showing my new design, in closed position;

Fig. 2 is an end elevational view thereof;

Fig. 3 is a top elevational view;

Fig. 4 is a top plan view of biscuit box in open position with the compartment covers closed; and

Fig. 5 is a view similar to Fig. 4 with the compartment covers in raised position.

I claim:

The ornamental design for a biscuit box, as shown.

ARMAND M. GUIOR.
